UNITED STATES PATENT OFFICE.

DAVID S. KENNEDY, OF BROOKLYN, NEW YORK, ASSIGNOR TO MERICENTHALER LINOTYPE COMPANY, A CORPORATION OF NEW YORK.

TYPOGRAPHICAL COMPOSING-MACHINE.

1,115,209.

Specification of Letters Patent. Patented Oct. 27, 1914.

Application filed May 3, 1913. Serial No. 765,196.

To all whom it may concern:

Be it known that I, DAVID S. KENNEDY, a citizen of the United States, residing at Brooklyn, in the county of Kings and State 5 of New York, have invented certain new and useful Improvements in Typographical Composing-Machines, of which the following is a specification, reference being had therein to the accompanying drawing.

10 My invention relates to typographical composing machines, and more particularly to that class thereof known to the public under the name "linotype," and as illustrated, for instance, in Letters Patent of 15 the United States, to O. Mergenthaler, No. 436,532. In machines of this type, it is the common practice to make use of matrices representing characters other than those controlled by the keyboard. These extra or 20 "sorts" matrices are inserted by hand in the matrix line during composition, and are subsequently delivered by the distributor at a common point, from which ordinarily they descend by gravity through a 25 receiving tube into a pi-stacker or other receptacle at the front of the machine. Such a mechanism, generally speaking, is old in the art and is shown in Letters Patent of the United States to J. R. Rogers, No. 30 630,112.

In the more advanced and refined practice, machines have been devised wherein are employed a plurality of magazines, any one of which may be brought into operative 35 relation to the keyboard and escapement mechanism at will, this result being sometimes attained by shifting the magazines with reference to the other devices, and sometimes by leaving the magazines stationary and shifting some of the other mechanisms with reference thereto. Such a plurality of magazines is intended to provide a larger and more varied assortment of characters, which in turn may be again 45 supplemented by the employment of additional or sorts matrices, that are more rarely used and are not contained within the magazines or represented by the keyboard. These sorts correspond more or less 50 in their face or style to the particular face or style carried by the magazine in operation, and it is therefore desirable that they should be segregated in the same way that the primary matrices in the

magazines are kept separate. To this end, 55 therefore, I provide a plurality of receptacles for the sorts, so that the sorts appertaining to each magazine will be received in a separate receptacle, and will be readily available to the compositor without the necessity for searching through a mixed mass 60 thereof to discover the particular face or style desired.

My invention relates to a form of mechanism of the character above described, 65 illustrated as used, in connection with the machine set forth in Letters Patent of the United States to J. R. Rogers, Nos. 848,771 and 930,693, wherein a plurality of stationary magazines is employed in connection with a vertically adjustable sash frame, which carries the escapement actuating devices and may be brought into operative 70 relation to any selected magazine. As will appear from the specific description thereof, 75 the same principles are capable of different application and may also be adapted to distinctly different styles of typographical machines, such for instance as those which handle type or dies instead of matrices. 80 Generally speaking, I desire it to be understood that I do not limit myself to any particular form or embodiment, except in so far as such limitations are specified in 85 the claims.

Referring to the drawings: Figure 1 is a perspective view of a portion of a linotype machine of the class referred to, having my improvements embodied therein; Fig. 2 is a transverse vertical section through the 90 magazines; Fig. 3 is a section on the line 3-3 of Fig. 2; Fig. 4 is a perspective, on an enlarged scale, of the pi-stackers detached; and Fig. 5 is a section on the line 5-5 of Fig. 4. 95

The magazines A, of which four are shown, are mounted in permanent relation to the individual distributor rails or bars B, and the vertically movable assembling elements may be adjusted with reference 100 thereto in substantially the manner described in the previously mentioned Letters Patent, Nos. 848,771 and 930,693. As will be understood by those skilled in the art, the sorts matrices, representing characters 105 other than those controlled by the keyboard, are inserted by hand in the matrix line in course of composition, and are automatically

released by the distributor at a common point. In the present instance, the extra matrices X corresponding to the magazine in operation, are conveyed along the distributor rail B by the rotating screws C and pass therefrom through the last channel A' of such magazine, the tube section F, and the tube section G, into the sorts box H. In view of the fact that the sorts matrices X, corresponding to the particular font in operation, are delivered through the magazine containing that font, I employ a plurality of tube sections F, tube sections G, and sorts boxes H, or in other words, a set of the said parts for each of the magazines A. In the use of pi-stacking devices of this description, it has been customary in the past to cause the sorts matrices to pass from the sorts channel through an aperture 20 formed in the bottom of the magazine. However, such construction would be an inconvenient one in the present instance, where a number of magazines are superposed in close relation to each other, and, 25 therefore, I propose to take the matrices from the magazine laterally through an opening E formed in the edge thereof and communicating with the sorts channel A'. In order to deflect the matrix through the 30 opening E into the tube section F, I provide the block D, which is mounted in the channel A' and is formed with an inclined end located in proximity to the opening E, in such manner that the matrix is directed 35 through the opening and into the tube section F, as clearly shown in Fig. 3.

In machines of the class described, the magazines A although stationary, are nevertheless replaceable by others containing different fonts, and for this purpose they are ordinarily removed at the front of the machine. Instead of being rectangular in form, the magazines are generally of considerably greater width at the rear than at 45 the front, and to permit them to be slid forwardly during removal, I also arrange the upper tube sections F so that they may be detached at will, and then restored to operative position after the change of magazines. 50 As a convenient means for obtaining this result, I employ a frame or receptacle H, wherein the sections F are mounted, and provide the frame with suitable means, such as the clamping device J, whereby it may be 55 readily connected to or disconnected from the magazines A.

Each of the sorts boxes H is equipped with means for advancing the matrices X therein, preferably in the form of the star wheel K (see Fig. 5), which is rotated by the shaft L, pulley M, belt N, and pulley O on the jack-shaft P, which shaft is in turn actuated by the pulley Q thereon and the belt R passing around the rotating pulley S. 65 Referring to Figs. 4 and 5, it will be seen

that the star wheels of all four of the sorts boxes H are actuated from the single shaft P, this result being accomplished by the employment of the two pulleys O thereon, the belt N from each of said pulleys operating 70 the pulleys M on the shafts L of two adjacent boxes. By this simple arrangement of actuating parts, I reduce their number as well as the space occupied thereby to a minimum. 71

As previously stated, I have shown my invention only in preferred form and by way of example, and as applied to a specific style of machine. Obviously, many modifications and alterations therein will suggest 80 themselves to those skilled in the art without departure from its scope.

Having thus described my invention, its construction and mode of operation, what I claim and desire to secure by Letters Patent 85 of the United States, is as follows:

1. In a typographical composing machine, the combination of a plurality of superposed flat magazines for the type or matrices, capable of independent use, and a corresponding plurality of sorts receiving devices, the parts being constructed in such manner that the sorts type or matrices are delivered laterally to the receiving devices through openings in the edges of the magazines. 95

2. In a typographical composing machine, the combination of a flat magazine for the type or matrices supported with its bottom face in close proximity to and obstructed by some other part of the machine, and a sorts receiving device, the magazine being formed with an opening in its side edge through which the sorts type or matrices pass sidewise into the receiving device. 100

3. In a typographical composing machine A having the sorts channel A' and supported with its bottom face in close proximity to and obstructed by some other part of the machine, with a sorts receiving device, the magazine being formed with the opening E at the side of the channel A' and provided with the block D to deflect the sorts type or matrices sidewise through the opening into the receiving device. 110

4. In a typographical composing machine, the combination of a plurality of magazines for the type or matrices, and a corresponding plurality of sorts receiving devices co-operating therewith, a portion of the sorts receiving devices being detachably mounted to permit the convenient removal of the magazines. 120

5. In a typographical composing machine, the combination of a plurality of magazines for the type or matrices, the said magazines being of greater width at their rear than at the front, with a corresponding series of sorts receiving devices co-operating 125 130

therewith, a portion of the sorts receiving devices being detachably mounted to permit the convenient forward removal of the magazines.

6. In a typographical composing machine, the combination of a plurality of magazines for the type or matrices, and a corresponding plurality of sorts receiving devices coöperating therewith, a portion of the sorts receiving devices being detachably connected to the magazines to permit the convenient removal of the magazines when desired.

7. In a typographical composing machine, the combination of a plurality of magazines A for the type or matrices, the said magazines being of greater width at their rear than at the front, with a corresponding plurality of sorts receiving devices coöperating therewith, the said devices comprising the tubes F and their supporting frame H, and detachable means J to

connect the frame to the magazines, in order to permit its disconnection and the ready forward removal of the magazines at will. 25

8. In a typographical composing machine, the combination of a plurality of magazines for the type or matrices, a corresponding plurality of sorts receiving devices coöperating therewith, of means for advancing the type or matrices in said receiving devices, and mechanism for actuating said advancing means, the said mechanism comprising pulleys M connected to each of the advancing means, the single shaft P, 30 the pulleys O thereon, and belts N connecting the pulleys M and pulleys O.

In testimony whereof I affix my signature in presence of two witnesses.

DAVID S. KENNEDY.
